STRAIGHTENING MACHINE

Benjamin P. Hazeltine, Wheeling, W. Va.

Application May 14, 1941, Serial No. 393,345

14 Claims. (Cl. 153—54)

This invention relates to the straightening of cylindrical blanks such as tubing, rods and like articles of circular cross section, and more particularly to apparatus in which such blanks are straightened by the threads or flights of rotating screws.

This invention is especially applicable to hot straightening as shown in my Patents Nos. 1,758,699 and 2,199,130. The machines shown in those patents are quite limited by the pitch of the straightening screws as to the sizes of blanks that they can straighten. Thus, a straightening machine for small diameter blanks will not straighten large blanks, and vice versa, wherefore it is necessary to have straightening machines of different sizes. This greatly increases the cost of straightening and requires considerably more floor space.

It is among the objects of this invention to provide a straightening machine of the general character disclosed in my above-mentioned patents which can be adjusted to accommodate blanks of many different sizes and which can straighten relatively long blanks as well as short ones.

In accordance with this invention a plurality of blank-straightening screw flights are rotatably mounted in spaced parallel relation in a substantially horizontal plane and are adapted when a blank is laid transversely thereof to engage it on opposite sides at longitudinally spaced points, thereby providing a series of three-point contacts. The engagement of the blank on opposite sides by the screw flights creates a forward thrust, due to the rear flights, which is opposed by the reaction of the forward flights, and the revolving flights cause the blank to rotate while moving it lengthwise and toward the delivery ends of the screws so that the thrust acting upon longitudinally spaced points along the blank is applied progressively to its periphery from end to end. In the case of a bent or kinked blank moving through the flights, unevenly distributed stresses will be created due to the tendency for the points of support to be out of line, and as the blank rotates the increased stresses applied to the bent portions act around the blank to bring it into line. To accommodate blanks of different outside diameters, the screws are so mounted that they can be swung laterally so that, in effect, their pitch is increased or decreased for receiving and straightening blanks of larger or smaller diameter. Preferably, there are located between some of the screws rollers that are rotated in a direction opposite to that of the

5 screws. As the blanks travel longitudinally of the screws they move up onto these rollers until the blanks are freed from the grip of the screws, whereupon the rollers quickly move the blanks longitudinally across the screws back toward the end of the machine at which they first engaged the screws so that they will not leave the machines before they have traversed the full length of the screws.

The preferred embodiment of the invention is illustrated in the accompanying drawings in which Fig. 1 is a plan view of my straightening machine; Fig. 2 is a combined side view and vertical section taken on the line II—II of Fig. 1; Fig. 3 is an enlarged transverse section taken on the line III—III of Fig. 1; Fig. 4 is an enlarged fragmentary view taken on the line IV—IV of Fig. 1; and Fig. 5 is an enlarged fragmentary end view taken on the line V—V of Fig. 1.

Referring to the drawings, a plurality of substantially parallel screw flights 1 are disposed in laterally spaced relation in a common horizontal plane. As shown in Fig. 3, at one side of the series of screws that end of each screw has its 10 projecting shaft journaled in the upper portion of a gear box 2 in which a bevel gear 3 is rigidly mounted on the shaft. This gear meshes with another bevel gear 4 on the upper end of a vertical shaft 6 journaled in the lower portion of the gear box from the bottom of which the shaft projects. Mounted on the lower end of this shaft is a bevel gear 7 that is driven by a similar gear 8 mounted on a horizontal line shaft 9 extending the full length of the machine. As shown in Fig. 15, this line shaft is journaled in housings 11 that rest on a suitable foundation and is rotated by a large bevel gear 12 at its center driven by a bevel pinion 13 from a motor 14 disposed at the side of the machine. The opposite end of each screw is journaled in a bearing supported in a manner to be described presently.

The screws are preferably arranged in spaced groups and disposed between the groups of gear boxes 2 are brackets 16 projecting therefrom. Mounted on some of these brackets are electric motors 17 each of which drives a roller 18 journaled on a horizontal axis at the entry end of the adjacent screws. The tops of these rollers are above the tops of the screws so that when a blank, such as a pipe, is deposited on the rollers at the right-hand end of the machine as viewed in Figs. 1 and 2, they will carry it lengthwise of the machine to the opposite end thereof where it will strike a suitable stop 19. Due to the length of the pipes it is not necessary that the rollers

be located throughout the length of the machine, but their place can be taken near the left-hand end by small idle rollers 21 mounted on brackets 16 as shown in Fig. 1.

Between the rollers there are short lengths of a trough 22 that aids in supporting and guiding the pipes as they are carried forward by the rollers. The trough is open along the side facing the screws so that pipes can be pushed laterally out of it and onto the screws by kick-off members disposed between some of the trough sections. Each kick-off member consists of a horizontal arm 23 mounted at the back of the trough at the upper end of a vertical rotatable shaft 24 the lower end of which carries a laterally projecting lever 26 (Fig. 3). Connecting these levers are rods 27 which are periodically pulled by an electrically operated mechanism 28 (Figs. 1 and 2) at one end of the machine in order to swing arms 23 across the trough and thereby push a pipe onto the screws. Disposed between some of the screws are cross bars 29 (Fig. 1) which can be raised by hand levers 30 suitably connected to them at one end so that in case anything goes wrong with the machine the pipes can be raised by the bars out of engagement with the screws to avoid damage.

It is a feature of this invention that this machine can be adjusted to accommodate blanks of larger or smaller outside diameter than it will accommodate when the screws are in the position shown in Fig. 1. Accordingly, the screws are so mounted that one end can be swung laterally in either direction as indicated by the broken lines beside the end screws. To permit this lateral adjustment the lower portion of each gear box 2 is encircled by a horizontal flange 36 that rests on an annular shoulder 37 formed in an upwardly projecting cylindrical portion of shaft housing 11, as shown in Figs. 3 and 4. The gear box is thus adapted to be turned on a vertical axis relative to the shaft housing supporting it. The bearing 38 for the other end of each screw rests on a draw-plate 39 extending the full length of the machine and slidably supported on a horizontal I-beam 41 mounted on a suitable foundation. These bearings 38 are pivotally connected to the draw-plate by an integral pin 42 projecting downwardly from the bottom of each bearing into an opening in the draw-plate. The bearings are thus all spaced predetermined distances apart so that the screws will be maintained parallel when adjusted laterally. The bearings are held on the screws by means of tie rods 43 connecting the bearings to gear box 2 as shown in Fig. 3.

As shown in Figs. 1 and 5, rigidly mounted on one end of the draw-plate is a rack 45 having transverse teeth on its upper surface meshing with a pinion 46 mounted on a shaft 47 journaled in a yoke 48 extending across the top of the draw-plate and supported by a transverse beam 49 connected to the I-beam. One end of this shaft projects from the yoke and carries a gear 51 which meshes with a pinion 52 driven by an electric motor 53. Thus, when this motor is driven, pinion 46 moves the rack and attached draw-plate either to the left or right, thereby swinging in the corresponding direction the ends of the screws that are pivotally attached to the draw-plate. During this movement the draw-plate travels in an arc, wherefore it slides laterally on I-beam 41 as it slides longitudinally thereof. Consequently, the rack is made wider

than pinion 46 so that it will remain in engagement with the pinion as the rack moves laterally beneath it.

When the draw-plate is moved to the right as viewed in Fig. 1 the pitch of the screws is, in effect, decreased so that they can grip and effectively straighten smaller pipes. If the draw-plate is moved to the left the pitch of the screws is increased so that larger pipes can be accommodated between their flights and be straightened thereby.

Another feature of this invention is that, regardless of the length of the pipes being straightened, their movement lengthwise of the machine is controlled in such a manner that they will not run off the right-hand end of the machine before they reach the delivery ends of the screws. That is, if it were not for the feature about to be described long pipes would reach the right-hand end of the machine long before they could reach the delivery ends of the screws. This problem is solved by this invention by mounting rollers 56 between at least some of the groups of screws, the tops of the rollers extending up between the screws far enough to support pipes out of gripping relation with the screw flights as shown in Fig. 3, so that the rollers can move the pipes lengthwise back toward the left-hand end of the machine at which they started their travel across the screws. The rollers are journaled in bearings 57 mounted on a table 58 and are driven by chain and sprocket drives 59 from a motor 61 suspended from one end of the table. The end of each roller adjacent the entry end of the screws is tapered so that as a pipe is moved laterally by the screws it will be rolled up the tapered ends of the rollers and onto the cylindrical portions thereof out of the grip of the screw flights. These rollers are rotated quite rapidly so that as soon as the pipe is released from the grip of the screws it is quickly moved back to the left-hand end of the machine where it is stopped by stop 19. As soon as the pipe rolls off the opposite end of the rollers it is again gripped by the screws and carried back toward the right-hand end of the machine which a long pipe will reach substantially at the time it leaves the delivery ends of the screws. Thus, a relatively short straightening machine is adapted to straighten relatively long pipes.

For short pipes which do not need to be moved back across the table by rollers 56, or for pipes of larger or smaller diameter which may ride in the screws at different levels, the roller table 58 can be lowered to an inoperative position or raised to the desired height. For this purpose the table rests on a frame 62 (Figs. 2 and 3) which is supported by levers 63 rigidly mounted on horizontal shafts 64 pivoted in a framework 66. Also rigidly connected to the center of each shaft 64 is a downwardly extending lever 67 the lower ends of which are connected by a rod 68. The lever at one end of the framework is connected by a screw 69 to a bracket 71 projecting from the framework. By adjusting this screw through the bracket the frame and table can be raised or lowered by levers 63.

It is also desirable to be able to adjust the roller table longitudinally when the screws are swung laterally so that the screws will not strike the rollers. Accordingly, the roller table is slidably mounted on frame 62 and can be adjusted lengthwise thereon by means of a screw 72 threadably mounted in one end of the table and

rotatably mounted in an upright bearing 73 at the adjacent end of the frame. This screw can be turned by a hand-wheel 74.

Although only one row of rollers 56 has been illustrated, it will be obvious that for a shorter machine or for still longer pipes one or more additional rows of like rollers can be mounted in the same manner between the screws so that pipes will be returned by the rollers to the left-hand end of the machine more than once.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A machine for straightening cylindrical blanks, comprising a plurality of laterally spaced screw flights disposed in a common plane, said flights being formed to receive a blank transversely thereof and to engage it on opposite sides at longitudinally spaced points, means for rotating said screws to rotate and straighten the blank while conveying it longitudinally of the screws, and means for swinging the screws on axes perpendicular to said plane to position said flights for receiving and straightening blanks of larger or smaller outside diameter.

2. A machine for straightening cylindrical blanks, comprising a plurality of laterally spaced screw flights disposed in a common plane, said flights being formed to receive a blank transversely thereof and to engage it on opposite sides at longitudinally spaced points, means for rotating said screws to rotate and straighten the blank while conveying it longitudinally of the screws, and means for swinging all of the screws the same number of degrees on axes perpendicular to said plane to position said flights for receiving and straightening blanks of larger or smaller outside diameter.

3. A machine for straightening cylindrical blanks, comprising a plurality of laterally spaced parallel screw flights wound in the same direction, said flights being formed to receive a blank transversely thereof and to engage it on opposite sides at longitudinally spaced points, means for rotating said screws to rotate and straighten the blank while conveying it longitudinally of the screws, and means for swinging all of the screws laterally in the same direction to position said flights for receiving and straightening blanks of larger or smaller outside diameter.

4. A machine for straightening cylindrical blanks, comprising a plurality of laterally spaced parallel screw flights wound in the same direction, said flights being formed to receive a blank transversely thereof and to engage it on opposite sides at longitudinally spaced points, means for rotating said screws to rotate and straighten the blank while conveying it longitudinally of the screws, and means for simultaneously swinging all of the screws laterally in parallel relation to position said flights for receiving and straightening blanks of larger or smaller outside diameter.

5. A machine for straightening cylindrical blanks, comprising a plurality of laterally spaced screw flights disposed in a common plane, said flights being formed to receive a blank transversely thereof and to engage it on opposite sides at longitudinally spaced points, means for rotating said screws to rotate and straighten the

blank while conveying it longitudinally of the screws, means pivotally mounting one end of each screw on an axis perpendicular to said plane, and means for swinging the opposite end 5 of each screw around said axis to position said flights for receiving and straightening blanks of larger or smaller outside diameter.

6. A machine for straightening cylindrical blanks, comprising a plurality of laterally spaced 10 screw flights disposed in a common plane, said flights being formed to receive a blank transversely thereof and to engage it on opposite sides at longitudinally spaced points, means for rotating said screws to rotate and straighten the 15 blank while conveying it longitudinally of the screws, means for swinging the screws on axes perpendicular to said plane to position said flights for receiving and straightening blanks of larger or smaller outside diameter, and means 20 between at least some of said screws for raising the blanks out of straightening relation with said flights and for moving the blanks longitudinally across the screws.

7. A machine for straightening cylindrical 25 blanks, comprising a plurality of laterally spaced screw flights disposed in a common plane, said flights being formed to receive a blank transversely thereof and to engage it on opposite sides at longitudinally spaced points, means for rotating 30 said screws to rotate and straighten the blank while conveying it longitudinally of the screws, means for swinging the screws on axes perpendicular to said plane to position said flights for receiving and straightening blanks of larger 35 or smaller outside diameter, rollers between at least some of said screws for raising the blanks out of straightening relation with said flights, and means for driving said rollers in a direction opposite to the direction of rotation of the screws 40 to move the blanks longitudinally back across the screws in the direction from whence they came.

8. A machine for straightening cylindrical 45 blanks, comprising a plurality of laterally spaced screw flights disposed in a common plane, said flights being formed to receive a blank transversely thereof and to engage it on opposite sides at longitudinally spaced points, means for rotating 50 said screws to rotate and straighten the blank while conveying it longitudinally of the screws, means for swinging all of the screws the same number of degrees on axes perpendicular to said plane to position said flights for receiving and straightening blanks of larger or smaller outside 55 diameter, rollers between at least some of said screws, said rollers being tapered toward the entering ends of the screws for temporarily raising the blanks out of straightening relation with said flights, and means for driving said rollers in a direction opposite to the direction of rotation of the screws to move the blanks longitudinally back across the screws in the direction from whence they came.

9. A machine for straightening cylindrical 65 blanks, comprising a plurality of laterally spaced screw flights disposed in a common plane, said flights being formed to receive a blank transversely thereof and to engage it on opposite sides at longitudinally spaced points, means for rotating 70 said screws to rotate and straighten the blank while conveying it longitudinally of the screws, means for swinging the screws on axes perpendicular to said plane to position said flights for receiving and straightening blanks of larger or smaller outside diameter, rollers between at least some of said screws for raising the

blanks out of straightening relation with said flights, means for adjusting the rollers laterally to accord with the swinging of the screws, and means for driving said rollers in a direction opposite to the direction of rotation of the screws to move the blanks longitudinally back across the screws in the direction from whence they came.

10. A machine for straightening cylindrical blanks, comprising a plurality of laterally spaced screw flights disposed in a common horizontal plane, said flights being formed to receive a blank transversely thereof and to engage it on opposite sides at longitudinally spaced points, means for rotating said screws to rotate and straighten the blank while conveying it longitudinally of the screws, means for swinging the screws on vertical axes to position said flights for receiving and straightening blanks of larger or smaller outside diameter, rollers between at least some of said screws for raising the blanks out of straightening relation with said flights, means for adjusting the rollers vertically relative to the screws, and means for driving said rollers in a direction opposite to the direction of rotation of the screws to move the blanks longitudinally back across the screws in the direction from whence they came.

11. A machine for straightening cylindrical blanks, comprising a plurality of laterally spaced screw flights disposed in a common plane, said flights being formed to receive a blank transversely thereof and to engage it on opposite sides at longitudinally spaced points, means for rotating said screws to rotate and straighten the blank while conveying it longitudinally of the screws, a shifting member movable in said plane and located adjacent one end of the screws, means pivotally mounting the adjacent ends of the screws in said member on axes perpendicular to said plane, and means for moving said member in said plane to simultaneously swing all of the screws laterally to position said flights for receiving and straightening blanks of different diameters.

12. A machine for straightening cylindrical blanks, comprising a plurality of laterally spaced screw flights disposed in a common plane, said

flights being formed to receive a blank transversely thereof and to engage it on opposite sides at longitudinally spaced points, means for rotating said screws to rotate and straighten the blank while conveying it longitudinally of the screws, a slide plate located adjacent one end of the screws, bearings for said ends of the screws and pivotally mounted in said plate, and means for sliding said plate in said plane to simultaneously swing all of the screws laterally to position said flights for receiving and straightening blanks of different diameters.

13. A machine for straightening cylindrical blanks, comprising a plurality of laterally spaced screw flights disposed in a common plane, said flights being formed to receive a blank transversely thereof and to engage it on opposite sides at longitudinally spaced points, means for rotating said screws to rotate and straighten the blank while conveying it longitudinally of the screws, a slide plate located adjacent one end of the screws, bearings for said ends of the screws and pivotally mounted in said plate, a rack mounted on said plate, a pinion meshing with the rack, and means for driving the pinion to slide said plate in said plane whereby to simultaneously swing all of the screws laterally to position said flights for receiving and straightening blanks of different diameters.

14. A machine for straightening cylindrical blanks, comprising a plurality of laterally spaced screw flights disposed in a common plane, said flights being formed to receive a blank transversely thereof and to engage it on opposite sides at longitudinally spaced points, a gear box adjacent one end of each screw mounted for rotation on an axis perpendicular to said plane, the end of the adjacent screw projecting into each gear box, a source of power, gearing operatively connecting said source of power to the end of the screw projecting into each gear box, and means for swinging the opposite ends of the screws on the axes of the gear boxes to position said flights for receiving and straightening blanks of different outside diameters.

BENJAMIN P. HAZELTINE.
